FIREARM

Marriner A. Browning, Ogden, Utah, assignor to
 J. M. & M. S. Browning Company, Ogden,
 Utah, a corporation of Utah

Original application May 27, 1935, Serial No.
 23,561. Divided and this application June 2,
 1936, Serial No. 83,048

4 Claims. (Cl. 42—70)

This invention relates to firearms and particularly to a firearm of the lever action type and is a division of my application Serial No. 23,561 filed May 27, 1935, to which reference may be 5 had for details not incorporated as a part of this application.

The aim of the present invention is to provide a simple and effective firing mechanism wherein accidental operation of the sear and firing of the 10 firearm due to shock or jar are prevented.

Other objects will be in part obvious and in 15 part pointed out more in detail hereinafter.

The invention accordingly consists in the features of construction, combination of elements 20 and arrangement of parts which will be exemplified in the construction hereinafter set forth and the scope of the application of which will be indicated in the appended claims.

In the accompanying drawings:

Figure 1 is a sectional view taken generally 25 longitudinally and vertically through the receiver of my firearm and shows the various parts in their normal or firing positions;

Fig. 2 is a rear view of the receiver or frame;

Fig. 3 is a transverse sectional view through 30 the receiver or frame, the same being taken on line 3—3 of Fig. 1;

Fig. 4 is a view similar to Fig. 1 but showing the operating lever in forward position;

Fig. 5 is an elevational view looking at the 35 right-hand side of the detached breech block;

Fig. 6 is a front view of the breech block; and

Fig. 7 is a bottom plan view thereof.

Referring to the drawings in detail, 10 designates the usual combined stock and forearm generally of the military type; 11 is the barrel, and 12 designates the receiver or frame of suitable construction. In the present illustrative disclosure, this receiver has a parti-cylindrical breech receiving portion 13 and a pair of depending spaced parallel flanges 14. Secured to the forward end and constituting a part of the receiver is a barrel attaching member in the form of a 15 ring 15 having a depending web or block 16 secured between the forward portions of the flanges by rivets 17. Between the cylindrical portion 13 and the ring 15 is the usual loading and ejecting opening 18. The block 16 extends downwardly 20 to the lower edges of the flanges 14 and its rear face constitutes a guide for a magazine 19. Located between the flanges 14 at their rear lower corners is a block 22 secured in place by rivets 23. A safety is supported by this block, as hereinafter described more in detail. At the rear 25

end of the cylindrical portion of the receiver is a ring portion 24 which is internally threaded to receive a plug 26 supporting a rear sight 27. There is further provided between the flanges a cross block 28 which serves as a lock abutment 30 and as a guide for the trigger connector. It is secured in place by rivets 29.

Mounted for reciprocation in the cylindrical portion of the frame is a breech block similar in construction to that shown in my copending application Ser. No. 23,561 and which comprises generally a cylindrical steel rod or bar 35 having its forward end slabbed or cut-away on its under side so as to clear the magazine. At the forward end and on opposite sides of the breech block are 35 the usual spring pressed extractors 36 which need not be described in detail here as their construction and operation are well-known in the art. The breech block is bored out so as to accommodate a striker 40 having the usual firing pin 41 40 adapted to strike against the rim of a cartridge. Intermediate its ends, the striker is vertically slotted, so as to accommodate a cam 43 on the upper end of an operating lever 44. The striker, on its under side, is provided with a sear notch 45. A main spring 47 compressively engages 45 against the rear of the striker.

The breech block is longitudinally slotted on its under side, as at 50, so as to accommodate a sear 51 having the usual sear notch at its forward 50 end adapted to cooperate with the notch 45 in the striker. The sear is pivoted on a pin 52 and is normally urged into holding or cocked position by a sear spring 53. The sear is connected to a trigger 54 by a connector 55 supported within a slot 56 in block 28. The trigger is pivoted at its forward end on a pin 59. The block 22, at the lower rear corner of the receiver, is slotted, as at 61, so as to accommodate a rearwardly extending projection 69 on the trigger when the latter 40 is pulled. The trigger also has a hooked shaped projection 62, the end of which is adapted to engage a pin 63 carried by said block so as to limit the downward movement of the trigger. Adapted to extend into the slot 61 is a safety 68 comprising a transversely shiftable member having a notch 64 adapted, when the safety is in "off" position and the trigger is pulled, to accommodate a lug 65 on the trigger. As is usual, when the safety is moved to "on" position, the slot is 50 moved out of registry with said lug so that the trigger cannot be pulled. The safety is maintained against turning by a pin 66. This pin has another function which will be described later.

In accordance with the present invention, the 55

firing mechanism is such that accidental operation of the sear and firing of the gun due to a shock or jar are prevented. In this instance, the rear end of the sear has a hooked portion 70, the notch of which faces forwardly. The connector 55 is pivoted between its ends to the cross block 28 as at 71. The connector has a vertical slot 72 which accommodates the pin 71 and permits a vertical sliding movement of the connector 10 within slot 56. Slot 56 is of such size that the connector fits loosely therein and is free for a slight pivotal movement on pin 71. The connector has, at its upper end, a rearwardly extending lug 73 adapted to engage in the notch 15 provided by the hooked portion 70 of the sear. The trigger has between its ends a recessed portion 74 having a pin 74' extending thereacross, and the lower end of the connector 55 has a horizontally extending notch 75 which receives 20 this pin. A spring 76 serves to urge the connector into sear engaging position and also serves to urge the trigger into unpulled or normal position. This spring is coiled about a pin 77 and has one end engaging the rear face of the connector 55 below the pivot 71 thereof to aid in maintaining lug 73 in the notch provided by hooked portion 70. The other end of the spring engages on the top of the projection 62 of the trigger. With this arrangement, it will be seen 25 that, when the safety is "on", the trigger, the connector, and the sear are positively locked in the positions shown in Fig. 1 and, therefore, the sear cannot be jarred out of striker holding position. When it is desired to fire the gun, the safety is moved to "off" position, and the trigger is pulled. Pulling of the trigger raises the connector, (vertical movement of the same being permitted by the slot 72) and the tail end of the sear is raised so as to disengage the sear from 30 the sear notch 45 in striker 40 whereupon the latter will move forwardly with a quick, sharp movement under the influence of the main spring 47. The purpose of permitting a slight pivotal action of the connector is to insure that the connector will properly engage the sear, in the event they may not be properly lined up at the time of initial engagement of the sear with the connector as the breech block is moved forwardly.

The mechanism for operating the breech block, which is similar to my copending application Ser. No. 23,561, generally comprises the lever 44 pivoted by a pin 91 to the breech block so that the cam 43 extends into the vertical slot in the breech block. The lever projects down between the flanges of the receiver and through a slot in the trigger plate and has, at its lower or free end, the usual handle in the form of an elongated loop. This handle normally lies closely adjacent to the pistol grip provided on the stock. The operating lever is pivotally connected to the receiver through the instrumentality of a link 94. The link is pivoted between the flanges of the receiver on a pin 95. The link is slotted so as to receive the lever and is pivoted to the lever by a pin 96. The lever 44 has, beneath its pivot with the breech block, a rearwardly extending arm 97 of such length that, when the lever is in the position shown in Fig. 1, the rear end of this arm engages the front face of the cross block. The arm 97 is provided, adjacent its rear end, with an upwardly extending locking lug 98 adapted to be received in a cross notch 99 on the under side of the breech block. The lever is 5 releasably held in its rearmost position shown

in Fig. 1 by the spring pressed pin 66 which projects rearwardly slightly beyond the block and is adapted to be received in a recess in the lever, as shown.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a firearm, a receiver, a breech block 20 slidably mounted therein, a striker slidably mounted in said breech block, a sear pivoted to said breech block and adapted to cooperate with said striker to hold the same in cocked position, a trigger, a safety directly cooperating with said trigger for preventing pulling thereof, and a connector engageable with said trigger and sear and adapted to release the sear from the striker when the trigger is pulled, said connector and sear having interengaging means for preventing the sear 30 from being jarred out of striker holding position when said safety is in "on" position.

2. In a firearm, a receiver, a breech block 35 slidably mounted therein, a striker pivoted to the breech block and adapted to cooperate with the striker to hold the same in cocked position, a trigger pivoted to said receiver, a safety directly associated with said trigger, and a connector connected to said trigger, said sear having a tail end provided with a hooked portion and the upper end of said connector having a rearwardly extending lug adapted to engage in said hooked portion whereby jarring of the sear from striker holding position is guarded against while the safety is 45 "on".

3. In a firearm, a receiver, a breech block 50 slidably mounted therein, a striker slidably mounted in the breech block, a sear pivoted to said breech block and having a tail end provided with a hooked portion, a trigger pivoted to the receiver, a safety engageable with the trigger to prevent its operation, and a connector between the trigger and the sear comprising a member pivotally and slidably mounted in the receiver and having 55 at its upper end a rearwardly extending lug engaging in the hooked portion of said sear at all times when the striker is in firing position.

4. In a firearm, a receiver, a breech block 60 slidably mounted therein, a striker slidably mounted in the breech block, a sear pivoted to said breech block and having a tail end provided with a hooked portion, a trigger pivoted to the receiver, a safety directly engageable with the trigger, a connector between the trigger and the sear comprising a member pivotally and slidably mounted on the receiver and having at its upper end a rearwardly extending lug engaging in the hooked portion of said sear when the striker is in firing position, means pivotally and slidably connecting the lower end of the connector to the trigger, and a spring normally urging said trigger to normal position and normally urging the lower end of said connector forwardly.

MARRINER A. BROWNING.
